UNITED STATES PATENT OFFICE.

WILLIAM SCHAAKE, OF PITTSBURGH, PENNSYLVANIA, ASSIGNOR TO WESTINGHOUSE ELECTRIC AND MANUFACTURING COMPANY, A CORPORATION OF PENNSYLVANIA.

SPLICER FOR TROLLEY-CONDUCTORS.

1,206,259.

Specification of Letters Patent. Patented Nov. 28, 1916.

Application filed August 7, 1911. Serial No. 642,881.

To all whom it may concern:

Be it known that I, WILLIAM SCHAAKE, a citizen of the United States, and a resident of Pittsburgh, in the county of Allegheny and State of Pennsylvania, have invented a new and useful Improvement in Splicers for Trolley-Conductors, of which the following is a specification.

My invention relates to splicers for trolley conductors, and it has for its object to provide a device of this character which shall be of greater strength and more effective and durable in service than similar devices heretofore employed.

15 The single figure of the accompanying drawing, which illustrates my invention, is a view, partially in side elevation and partially in section.

20 The general outline and structural characteristics of the splicer 1 are well known in the art the casting 2 of which may be of brass, bronze or other suitable composition and be provided, at each end, with a longitudinal channel 3 having an open bottom 25 and an inclined tubular recess 4 which constitutes a continuation of the channel 3 to receive an end of a trolley conductor, indicated in dotted and broken lines, the end of the trolley conductor to be spliced to that 30 just mentioned being similarly located at the other end of the casting 2.

35 The inner end of the recess or passage 4 is enlarged to provide a cylindrical seat 5 terminating in a shoulder 6. A cylindrical sleeve 7 is fitted closely into the seat 5 and is provided with a tapered inner surface to receive a chuck 8 having correspondingly tapered outer surface and being split longitudinally to grip the trolley conductor when 40 driven into place. The inner surface of the chuck is preferably provided with projections or serrations, as indicated, to more securely grip the trolley conductor.

45 The sleeve 7 is preferably formed of steel or some alloy or composition of great strength, so as to receive the pressure exerted by the chuck and relieve the casing from the strains incident to such pressure, and it is preferably shorter than the seat 5, 50 the material at the outer end of the seat being upset, as indicated at 9, to lock the sleeve in position. The shoulder 6 insures the retention of the sleeve in its proper position in the casing and also receives such

strains as may be exerted by the longitudinal 55 pull upon the trolley conductor.

I claim as my invention:

1. A trolley-wire splicer comprising a body member having a wire-holding recess that is open at each end, an integral annular shoulder intermediate the ends of said recess, a sleeve having a tapered inner surface disposed in one end of said recess with one end seated against said shoulder, and a 60 tapered split chuck seated in said sleeve. 65

2. A trolley-wire splicer comprising a casting having a wire-receiving socket that is open at each end, an integral annular shoulder intermediate the ends of said socket, an internally tapered steel sleeve disposed in one end of said socket and seated against said shoulder, an upset portion of 70 said casting for locking said sleeve within said socket and a longitudinally split chuck fitted into said sleeve. 75

3. A trolley-wire splicer comprising a body having a wire-receiving socket open at both ends and provided with an annular shoulder intermediate its ends, an internally tapered sleeve fitted into said socket and 80 having one end in engagement with said shoulder, a longitudinally split chuck fitted into said sleeve and provided with wire-gripping projections on its inner surface.

4. A trolley-wire splicer comprising a 85 body member having a longitudinal groove and a communicating inclined tubular opening extending through said member for receiving an end of a wire conductor, said member being provided with an annular 90 shoulder intermediate the ends of said opening, a sleeve having a tapered inner surface disposed in the end of said opening removed from said groove and having its inner end seated against said shoulder, and a tapered 95 split chuck having wire-gripping projections seated in said sleeve.

5. A trolley-wire splicer comprising a body member having a wire-receiving tubular recess therethrough and provided with 100 an integral annular shoulder intermediate the ends of said recess, a sleeve having a tapered inner surface disposed in one end of said recess and having an end thereof seated against said shoulder and a tapered 105 split chuck seated in said sleeve for co-operative engagement with said wire conductor and adapted to grip said conductor when

it is placed in tension, said sleeve and said chuck being removable from said recess in a direction away from said shoulder.

6. A trolley-wire splicer comprising a body member having oppositely projecting ends provided with bottom grooves to receive the ends of wire conductors and also having symmetrically disposed inclined tubular wire-receiving openings respectively communicating with said grooves and extending through said body member, each of said openings being constricted intermediate its ends to form an annular shoulder, a cylindrical sleeve inserted in the portion of each tubular opening removed from said

groove and having its inner end seated against said shoulder, said sleeve being provided with a tapered inner surface, and a tapered split chuck provided with wire-gripping projections seated in said sleeve 20 and removable therefrom away from said shoulder.

In testimony whereof, I have hereunto subscribed my name this 31st day of July, 1911.

WILLIAM SCHAAKE.
